TONSILLECTOME

Filed Sept. 25, 1931

UNITED STATES PATENT OFFICE

ULYSSES SCOTT SMITH, OF HANNIBAL, MISSOURI

TONSILLECTOME

Application filed September 25, 1931. Serial No. 565,173.

The present invention relates generally to surgical instruments and more particularly to a tonsillectome and has for its primary object to provide, in a manner as hereinafter set forth, an instrument of this character embodying a novel construction, combination and arrangement of parts through the medium of which the tonsil is crushed off, thereby limiting hemorrhage resulting from the 10 operation.

Another important object of the invention is to provide a tonsillectome including a manually operable slideable snare of heavy wire and further including novel means for 15 mounting the snare on its carrier.

Another very important object of the invention is to provide a tonsillectome embodying novel means for engagement by the digits of the hand for manipulating the instrument 20 and controlling and actuating the same.

Other objects of the invention are to provide a tonsillectome of the character described which will be simple in construction, strong, durable, efficient and reliable in use 25 and which may be manufactured at low cost.

All of the foregoing and still further objects and advantages of the invention will become apparent from a study of the following specification, taken in connection with the 30 accompanying drawings wherein like characters of reference designate corresponding parts throughout the several views, and wherein:—

Figure 1 is a top plan view of the tonsillectome constituting the present invention.

Figure 2 is a view in vertical longitudinal section taken substantially on the line 2—2 of Figure 1.

Figure 3 is a detail view in top plan showing the means for connecting the snare to the carrier.

Figure 4 is a sectional view taken substantially on the line 4—4 of Figure 2.

Figure 5 is a sectional view taken substantially on the line 5—5 of Figure 3.

Figure 6 is a detail view in elevation showing the auxiliary actuator which is provided for use when unusual power on the carrier is desired.

Referring now to the drawings in detail,

it will be seen that the tonsillectome constituting the present invention comprises an elongated metallic bar 1 having a longitudinal slot 2 therein. At its inner end the slot 2 merges with a polygonal opening 3 provided in the bar 1. Formed integrally with the inner end of the bar 1 is a depending, arcuate finger 4 for abutting engagement with the ball portion of the hand adjacent the base of the thumb when the instrument is in use. Rising from the inner end portion of the bar 1 is an upwardly and rearwardly curved finger 5 for engagement between the base of the thumb and the base of the index finger when the instrument is in use. The base portion of the finger 5 is provided with a longitudinal opening 6 the purpose of which will be presently set forth.

On the outer end portion of the bar 1 is a guide 7 through which the snare to be presently described is operable. The outer end of the guide 7 is formed to provide an arcuate jaw 8 for cooperation with the aforementioned snare. All of the surfaces of the jaw 8 are rounded so that no cutting edges are 75 present.

Disposed beneath the jaw 8 is a bowl 9 for the reception of the severed tonsil. A web 10 bridges a lower portion of the slot 2 at an intermediate point in the bar 1. Rising from an intermediate portion of the bar 1 on opposite sides of the slot 2 are the posts 11, the purpose of which also will be presently set forth.

A carrier 12 is operable longitudinally in the slot 2, said carrier having its forward portion upwardly offset, as at 13, and operable above the web 10. At its inner end the carrier has formed integrally thereon an upstanding head 14 having a longitudinal threaded opening 15 therein which is aligned with the opening 6. The head 14 is passed through the opening 3 when mounting the carrier 12 in position or when removing said carrier.

The reference numeral 16 designates a raised intermediate portion of the carrier 12. At its forward end the raised portion or rib 16 terminates in a point and formed integral- ly thereon is a guard 17. The guard 17 is 100

raised with respect to the bar 1 and is substantially of the configuration of an arrow head.

The reference numerals 18, 19 and 20 designate longitudinally spaced upstanding posts on the outer end portion of the carrier 12. The posts 19 and 20 are substantially T-shaped, as illustrated to advantage in Figure 5 of the drawings. The reference numeral 21 designates a snare of heavy wire which is bent to define a loop and the end portions of which are engaged with the posts 18, 19 and 20 and the guard 17 in the manner best seen in Figure 3 of the drawings. The heads of the substantially T-shaped posts 19 and 20 prevent the wire from accidentally slipping off. The guard 17, in addition to retaining the free ends of the wire constituting the snare, also shields these ends to prevent injury by contact therewith. The snare 21 is thus mounted on the carrier 12 for reciprocation longitudinally in the guide 7.

Extending from a rear portion of the carrier 12 is a finger 22 which constitutes the main means for actuating the carrier. Extending upwardly from the carrier 12 at a point slightly forward of the finger 22 is a finger 23 which also is for engagement by a finger of the hand for actuating the carrier. A stop 24 rises from the carrier 12 in forwardly spaced relation to the finger 23.

The reference numeral 25 designates an auxiliary carrier operating device or member which includes a threaded shank 26 which is insertable through the opening 6 for threaded engagement in the opening 15 of the head 14 for operatively connecting said auxiliary actuator to the carrier. The actuator 25 is provided with an enlargement defining a shoulder 27 which is engageable with the finger 5. The reference numeral 28 designates a handle in the form of an eye for actuating the member 25. A threaded shank 29 rises from a rear portion of the carrier 12 and has threaded thereon a nut 30. The nut 30 travels above the bar 1 and prevents downward movement of the rear end portion of the carrier 12 through the slot 2 when the instrument is in use.

When in use, the finger 4 is engaged with the ball portion of the hand adjacent the base of the thumb and the crotch portion of the hand which is between the base of the thumb and the base of the index finger is engaged with the finger 5. The carrier 12 is in its forward position in which position, it will be noted, the stop 24 is spaced forwardly of the posts 11. The free end portion of the index finger is inserted between the stop 24 and the posts 11 and the second and, if desired, the third finger 22 of the carrier 12. The carrier is then drawn rearwardly until the stop 24 engages the nail of the index finger. The instrument is then manipulated to properly engage the snare 21 over the

tonsil. During this operation the disposition of the index finger between the stop 24 and the posts 11 will prevent accidental or unintentional actuation of the carrier 12 rearwardly. After the tonsil has been properly engaged, the index finger is removed from between the stop 24 and the posts 11, and, if desirable, or necessary, may be engaged with the upper portion of the finger 23 to assist in pulling the carrier rearwardly. The snare 21 co-acts with the arcuate jaw 8 to crush and then sever the tonsil. The construction of the device is such that the use of a comparatively large wire is permitted which is an important feature of the invention. This comparatively large wire forming the snare 21, in conjunction with the rounded surfaces, of the jaw 8 will result in first crushing the tissue and then severing the tonsil, thus completing a substantially bloodless operation.

In those comparatively rare cases where even greater power on the carrier 12 is necessary or desirable and can be applied by engaging the fingers of the hand with the fingers 22 and 23, the shank 26 of the actuator 25 is inserted through the opening 6 and engaged in the threaded opening 15 of the head 14 on the carrier. The actuator 25 is then rotated and, with the shoulder 27 abutting the finger 5 the carrier 12 will be drawn rearwardly, as will be apparent.

It is believed that the many advantages of a tonsillectome constructed in accordance with the present invention will be readily understood, and although the preferred embodiment of the invention is as illustrated and described, it is to be understood that changes in the details of construction, and in the combination and arrangement of parts may be resorted to which will fall within the scope of the invention as claimed.

What is claimed is:—

1. A tonsillectome comprising a bar, a jaw on one end of the bar, a carrier slidably mounted on the bar, a series of posts on the carrier and a snare mounted on the carrier, said snare comprising a length of wire bent to loop form and having its end portions operatively engaged with the posts in a manner to secure the snare in position on the carrier, certain of the posts being substantially T-shaped for retaining the wire constituting the snare thereon, and a raised guard on the carrier engageable with the ends of the wire forming the snare in a manner to retain and shield said ends.

2. A tonsillectome comprising an elongated bar having a longitudinal slot therein, a guide on one end of the bar, said guide projecting beyond said one end of the bar, an arcuate jaw on the free end of the guide, the surfaces of said jaw being rounded, a carrier mounted on the bar and slidably operable in the slot, a raised rib on an inter-

mediate portion of the carrier, a guard on one end portion of the rib, a series of upstanding posts on one end portion of the carrier, certain of the posts being substantially T-shaped, a snare detachably mounted on the carrier and operable through the guide for coaction with the jaw, said snare comprising a single length of heavy wire bent in loop form and having its end portions engaged 10 with the posts in a manner to retain the snare in position on the carrier, the ends of the wire being engaged with the rib beneath the guard, and means for actuating the carrier.

3. A tonsillectome comprising an elongated bar having a longitudinal slot therein, a jaw on one end of the bar, a carrier mounted on the bar and slidably operable in the slot, a snare mounted on the carrier for coaction with the jaw, fingers projecting from 20 the carrier for manually actuating said carrier, posts rising from the bar, a stop rising from the carrier, said stop and the posts being adapted to receive a finger of the hand there-between for preventing actuation of the carrier in one direction, and means on the other end of the bar for engagement by the hand.

4. A tonsillectome comprising an elongated bar having a longitudinal slot therein, a jaw on one end of the bar, a carrier mounted on the bar and slidably operable in the slot, a snare mounted on one end of the carrier for coaction with the jaw, a head on the other end of the carrier having a threaded opening therein, an upstanding finger on the 35 other end of the bar having an opening therein in longitudinal alignment with the opening in the head, an actuator rotatably insertable through the second named opening for threaded engagement with the head for actuating the carrier in one direction, and a shoulder on the actuator for abutting engagement with the finger.

In testimony whereof I affix my signature.
ULYSSES SCOTT SMITH.
